(57) **CLAIM**

The ornamental design for a tire supported table, as shown.

DESCRIPTION

FIG. 1 is a front perspective view of a tire supported table showing my new design;

FIG. 2 is a top plan view thereof;

FIG. 3 is a bottom plan view thereof;

FIG. 4 is a side elevational view thereof;

FIG. 5 is a side elevational view thereof;

FIG. 6 is a front elevational view thereof; and,

FIG. 7 is a rear elevational view thereof.

The broken line showing details of the base in FIG. 4 is included for the purpose of showing environmental portions of the tire supported table and forms no part of the claimed design. The broken lines in FIG. 3 indicate the boundaries of the claimed design, and the broken lines and areas within these lines form no part of the claimed design.
